GARMENT STRUCTURE

Gertrude Davenport, New York, N. Y.

Application March 22, 1947, Serial No. 736,505

1 Claim. (Cl. 2-73)

1

This invention relates to sleeveless garments and particularly to a garment adapted to serve as a dressing gown or bath robe.

The object of the invention is to provide such a garment in simple, inexpensive form easily and quickly put on and off and attractively form-clinging and neat in appearance, and preferably of terry cloth or similar soft fabric.

Other objects of the invention particularly in forming the garment as a complete unit with a minimum of parts and operations involved will appear from the following specification taken in connection with the accompanying drawings in which

Fig. 1 is a view of the garment structure spread out to show the interior construction;

Figs. 2 and 3 are front and rear views of the garment as worn, and

Fig. 4 is a sectional view of a detail on line 4-4 of Fig. 1.

As indicated in Fig. 1 the garment 5 is preferably formed from a single piece of cloth, particularly terry cloth, which is loose and flexible and self-draping.

The top edge 6 droops slightly from end to end, the bottom edge 7 being nearly straight. This, as illustrated in Fig. 3, gives an upward sweep on each side from the lowermost back center point while maintaining a substantially level lower hem.

The front overlap edge has an upper curvature 8 biased and merging at the waist line into a substantially vertical portion 9. The inner overlapped edge has a double curvature concave at the upper portion 10 and blending at about the waist line into the lower convex portion 11. This formation is determined by the edge pattern and by the gathering effect of the darts 12, 13 and 14 tapered in each direction from the waist line area, a section at the maximum of the gathered material being indicated at Fig. 4 on line 4-4 of Fig. 1. Such back structure brings the terry cloth at the back inward in form-clinging lines (Fig. 3) hugging the waist line and draping naturally downward as material is released by the tapering of the darts 12, 13, 14.

The garment is thus brought into an upper gathered portion which fits beneath the arm pits and around the waist and a lower skirt portion 16 falling free.

The upper edge has the fastening loop and button 18 and 19, the former being at the meeting point of edges 6 and 8 and the latter near the opposite end of the top edge 6 so that there is a desired overlap sufficient to allow for adjustment of the button 19 to comfortable form-fitting

2

snugness above and around the breast of the wearer (Fig. 2).

Similarly the waist loop 20 and button 21 conform the garment to the waist line bringing the top overlap 8 on the bias across one side of the breast in front to the waist line at the side and then draping the outer skirt edge substantially vertically downward with the inner skirt edge 11 extending at a counter-bias around toward the front and overlaid with increasing overlap from the top toward the bottom edge.

Thus the garment forms the upper waist portion with the exposed overlap 8 at a bias down to the skirt where the edge 9 becomes substantially vertical. The inner overlapped edge 10 extends vertically down to the skirt and there at 11 is biased toward the front for ample fullness.

This provides a form-fitting upper part and a free flowing skirt from even the most soft and flexible material, such as terry cloth used widely as toweling. The garment is quickly put on and fastened to serve as a bath or beach robe or negligee dressing gown.

The structure shown embodies the preferred formation from a single piece of cloth with hemming 25 running around all of the edges. A plurality of sections may be sewed together to form the one piece structure preserving the same general construction and various decorative designs, colorings and trimmings may, of course, be added as desired.

The principle of the invention is not confined to the embodiment shown but is intended to cover such modifications thereof as fall within the scope 35 of the appended claims.

I claim:

A one-piece sleeveless strapless garment of soft flexible cloth comprised of a panel having an upper bust-covering section adapted to fit over 40 the breast and under the arms of the wearer with self-supporting snugness and waist and skirt sections below said bust section, top and bottom edges on said panel formed substantially straight and joined by vertical overlapped and overlapping 45 side edges, the bust portion of the overlapping side edge extending angularly downward with increasing fullness and the waist and skirt portions of said overlapping edge extending substantially vertically downward from said bust portion while 50 said overlapped side edge at the bust portion extends vertically downward to the waist section and curves outward and downward to greater fullness at the skirt section, rear gatherings extending substantially vertically through the bust 55 and waist sections and into the skirt section,

fastening means comprising a top pair of fasteners, one positioned at the upper end of the overlapping side edge and the other at the top edge inward from the overlapped side edge and a second pair of fasteners at the waist section, one positioned at the said overlapping edge and the other spaced inward from said overlapped edge, said gatherings and fastenings cooperating to provide form-clinging lines at the waist and bust with the skirt edges freely draped and overlapped and the overlapping side edge at the side of the wearer.

GERTRUDE DAVENPORT.
